UNITED STATES PATENT OFFICE.

WILLIAM M. CONWAY, OF BALTIMORE, MARYLAND.

MEANS FOR CARRYING AND CONDUCTING ELECTRIC WIRES.

SPECIFICATION forming part of Letters Patent No. 268,389, dated December 5, 1882.

Application filed February 9, 1882. (No model.)

To all whom it may concern:

Be it known that I, WILLIAM M. CONWAY, of the city of Baltimore, and State of Maryland, have invented certain Improvements in 5 Means for Conducting Electric Wires, of which the following is a specification.

This invention relates to improved means for carrying telegraph, telephone, and other electric wires under ground.

10 In carrying out my invention I employ a series of blocks of terra-cotta or other non-electricity-conducting material, preferably cylindrical in form, having longitudinally extending slots adapted for holding and isolating the 15 wires, and means for their connection to form a continuous line. At points where the ends of wires are to be united the blocks are connected by pipes having nozzles which extend to the surface of the ground, and suitable caps 20 or plates, whereby the said nozzles may be closed water tight. These connecting-pipes are also employed at points where the direction of any or all the wires is to be changed, and they are fitted with deflecting-plates having 25 slots which correspond in general character with those in the blocks.

In the further description of my said invention which follows, reference is made to the accompanying drawings, forming a part hereof, and in which—

30 Figure I is a partly-sectional view of the invention, showing the same as located below the surface of the ground. Fig. II is a cross-section on an enlarged scale, taken on the 35 dotted line *x y*. Fig. III is a longitudinal section of a part of the invention, also on an enlarged scale. Fig. IV is a top or plan view, showing particularly the connecting-pipe. Fig. V is a similar view, showing the deflecting- 40 plate. Fig. VI represents a device which is used in the threading of wires through the slotted blocks, as hereinafter described.

Similar letters of reference indicate similar parts in all the views.

45 A A represent the blocks, which are made of terra-cotta or other insulating material. These blocks are preferably united in a manner similar to pipes—that is to say, they are provided with a bell end or mouth-piece, into 50 which the straight end of another block may be inserted and fastened by means of packing. I do not, however, limit myself to this mode

of attaching the blocks together, as there are many other methods of uniting them which might prove as satisfactory. The longitudinal 55 slots or channels in the blocks before alluded to consist of a series of vertical leaders, *a*, having branches *b*, which terminate in recesses or pockets *c*, in which the wires are held. The leaders *a* are each provided with an entrance-opening, *d*, through which the wires are threaded; and to prevent the end of the wire entering the leader before it shall have passed entirely through the block or series of blocks a cap slightly smaller than the entrance-opening 65 is secured over it. This cap is shown secured to the end of a piece of wire in Fig. VI of the drawings.

B is a pipe which serves to connect two blocks at a point where the ends of wires are 70 to be united, as shown in Fig. I, or where any or all of the wires are to be deflected to a branch pipe, as illustrated in Fig. V. In this last-named figure the deflecting-plate before described, and which is denoted by C, is shown 75 in position. The pipe B has a nozzle, D, which extends to the surface of the ground, and is covered with a lid, E. A gasket, *e*, is used to form a tight joint between the lid and the upper edge of the nozzle. It will be seen that the 80 nozzles D give convenient access to the wires from the surface of the ground and entirely obviate the necessity of having the blocks in two parts, with the upper portion removable.

I claim as my invention—

85 1. A block of terra-cotta or other similar substance, adapted for attachment to a similar block to form a continuous line having a series of longitudinally-extending channels, which consist of vertical leading-slots, both 90 ends of which terminate at points within the cross-sectional area of the block, with lateral branches ending in wire pockets or recesses, substantially as specified.

2. A wire conducting and isolating block 95 provided with vertical leaders and lateral branches, and having an enlarged channel connected with said leaders at some suitable point to form a threading or entrance opening, substantially as specified.

WM. M. CONWAY.
